UNITED STATES PATENT OFFICE.

FRANK M. WATKINS, OF CINCINNATI, OHIO.

UNLOADING DEVICE FOR UNDERDRIVEN CENTRIFUGAL EXTRACTORS.

Application filed January 5, 1922. Serial No. 527,181.

To all whom it may concern:

Be it known that I, FRANK M. WATKINS, a citizen of the United States, residing at Cincinnati, in the county of Hamilton and 5 State of Ohio, have invented certain new and useful Improvements in Unloading Devices for Underdriven Centrifugal Extractors, of which the following is a specification.

10 This invention relates to improvements in centrifugal extractors and relates to the underdriven type of extractor in which there is provided a load-carrying cage capable of being raised out of the rotatable basket to 15 elevated position for unloading and reloading.

The objects of this invention are to provide a centrifugal extractor in which the load-carrying cage can be raised by means 20 of a fluid actuated plunger together with a multi-way valve for controlling fluid to the plunger, such controlling means being located so as to be readily accessible to the operator; to provide such a cage as can be 25 swung around to position out of vertical alignment with the basket; to provide an electric motive means for rotating the basket together with means included in the motor circuit for preventing raising movement of 30 the basket during operation of the motor; to provide means for centering the cage in the basket and also means for determining the proper angular position of the plunger so as to insure the cage being in proper 35 vertical alignment with the basket preparatory to lowering the same thereinto.

Other objects of the present invention will be apparent from the following description and claims when considered together with 40 the accompanying drawings.

Fig. 1 is a plan view of my device; Fig. 2 is an elevation with parts broken away; Fig. 3 is a sectional detail view of the three-way valve; Fig. 4 is a diagrammatic showing of the electric connections through the motor and the electric control valve; Fig. 5 is a vertical section of the plunger taken on line 5—5, Figs. 7 and 8; Fig. 6 is a vertical transverse section taken on line 6—6, 50 Fig. 1; Fig. 7 is a horizontal section taken on line 7—7, Fig. 5; and Fig. 8 is a horizontal section taken on line 8—8, Fig. 5.

The main frame 1 supports the curb or casing 2 and also the bracket 3 upon which 55 is supported the electric motor 4 for driv-

ing the spindle 5 through the belt connection 6 in a well known manner. The basket 8 is secured upon the spindle 5 by means of the nut 9 which has a threaded portion extending upwardly into the centering stem 10 which has engagement with the hollow hub 11. Suitably secured to the hub 11 and extending radially therefrom are the partition members 12 which constitute a load-dividing means. The auxiliary bottom 13, 60 which is secured to the lower end of the hub 11, forms together with the partitions 12, the cage which is adapted to be raised out of the basket 8 for unloading and re-loading operations. The cage is adapted to 65 be raised up through the opening 14 provided in the top of the curb 2, this opening being closed by the cover 15, which is suitably hinged at 16 to the curb. This cover is provided with an opening 17 which is 70 partially closed by the sliding auxiliary cover 18 mounted for sliding movement upon the main cover 15 by means of the pins 19 and the slot 20. Extending through the opening 17 is the arm 21 having a forked 75 inner end 22 engaging the flange 23 provided upon the upper end of the hub 11 for the purpose of raising the cage out of the basket the cover 18 and arm 21 together constitute the means for locking the main 80 cover 15 closed. The other end of the arm 17 is fixedly mounted upon the upper reduced portion of the plug 24, the lower portion of which has screw threaded engagement at 25 with the upper end portion of 85 the hollow plunger 26. The lower end of the plunger 26 is closed by means of the plug 27 which has screw threaded engagement therewith. The gland 28 with suitable packing 29 is secured by means of the bolts 90 30 for the purpose of providing a fluid tight engagement with the plunger 26 as it reciprocates therethrough. I have provided upon the plunger 26 a collar 31 which is adapted 95 to engage the stops 32 and 33, it being noted 100 that the stops 32 are spaced so as to provide the communicating passages 34 between the upper and lower portions of the chamber surrounding the plunger. The chamber 35 is suitably supported upon the main frame 105 of the machine and is braced by means of the strap 37 bolted to the wall of the curb.

Fluid, as for instance water, is supplied to the chamber 35 through the pipe 38 which is controlled by means of the valve 39 and 110

also the three-way valve 40. The three-way valve is manipulated by means of the handle 41 and can be set so as to supply fluid through the inlet pipe 42, through the pipe 5 43, through the valve 39, when open, to the inlet pipe 38 for raising the plunger when it is desired to lift the load-carrying cage out of the basket for unloading. The valve 10 40 can also be set so as to cut off the supply of fluid through the pipe 42, and to permit discharge of the fluid from the chamber 35 out through the valve 39, the pipe 43 and the discharge pipe 45. The ports of the 15 valve 40 are indicated by reference numerals 46 and 47, the valve in the position illustrated in Fig. 3 being set for discharge of the fluid out through the pipe 45.

Referring to the diagram shown in Fig. 4, it will be seen that upon closing the 20 control switch 48, circuit will be established from the positive side 49 of the main line through the motor 4, through the contact 50, which is closed upon energizing of the single pole magnetic contactor 51, and out 25 to the negative side 52 to the main line. It will be noted that upon closing this same circuit the magnet 53 will be energized so as to cause the valve 39 to close. The valve 39 is open when the motor is idle. With 30 this arrangement, the motor 4 may be operated for rotation of the basket which encloses the load-carrying cage and the plunger will remain in lowered position, since valve 39 is closed during operation of the 35 motor. Upon completion of the extracting operation the switch 48 will be opened so as to stop the motor 4 and at the same time the magnet 53 will thereby be de-energized so as to permit the valve 39 to be opened by 40 a spring or in any other suitable manner and thus permit supply of fluid to the chamber 35. When the motor and basket have been stopped, the cover 18 will be 45 opened so as to permit raising of the main cover 15 preparatory to raising the arm 21. The handle 41 will now be manipulated so as to open the valve 40 for supply of fluid to the chamber 35 for the purpose of raising the plunger so that the cage can be swung 50 around to unloading position as indicated in dotted lines in Fig. 1. Upon unloading the cage and re-loading the same, it can be swung back to vertical alignment with respect to the basket and, upon setting the 55 valve 40 for discharge of the fluid from the chamber 35, the plunger will lower by gravity so as to bring the cage to position within the basket. With this arrangement it will be seen that since the closing of the 60 switch 48 will cause the valve 39 to be closed, it is impossible for fluid to be supplied to the chamber 35 while the motor 4 is in operation; with the result that the danger of raising the cage during rotation 65 of the basket is precluded. The series field

of the motor 4 is indicated by reference numeral 54 and the shunt field by reference numeral 55.

As a means of determining when the plunger 26 has been swung to proper position for vertical alignment of the cage so as to lower into the basket, I have provided the slot plunger 26 with the slot 56 in which engages the pin 57 mounted in the wall of the chamber 35, the pin 57 being provided 70 with the spring 36 for forcing the same into the slot. The screw plug 58 is a means of varying the tension of the spring 36. I have provided also an air valve 58^a to permit escape of air from the chamber 35 upon 75 supply of fluid thereto, this valve being closed as soon as such air has been expelled. Then when it is desired to discharge the fluid from the chamber 35, the valve 58^a can be opened for atmospheric pressure. 80

Having described my invention, I claim:

1. An extractor, comprising a curb, a load-carrying member rotatably and vertically movable in said curb, means for rotating said member, fluid actuated means for 90 elevating said member, and means whereby operation of said rotating means prevents the supply of fluid to said fluid actuated means.

2. In an extractor, the combination of a 95 curb, a load-carrying cage rotatably mounted within said curb, said cage being adapted also for raising and lowering movement out of and into said curb, fluid actuated means for raising said cage, means for supplying fluid to said fluid actuated means, means for rotating said cage, and means for simultaneously controlling the operation of said rotating means and said fluid supplying means. 100

3. In an extractor, the combination of a 105 curb, a load-carrying cage rotatably mounted within said curb, said cage being adapted also for raising and lowering movement out of and into said curb, fluid actuated means for raising said cage, means for supplying fluid to said fluid actuated means, motor means for rotating said cage, and electric means for controlling said motor means and said fluid supplying means, whereby the 110 cage can not be raised during operation of the motor. 115

4. In an extractor, the combination of a 120 curb, a load-carrying cage rotatably mounted within said curb, said cage being adapted also for raising and lowering movement out of and into said curb, fluid actuated means for raising said cage, means for supplying fluid to said fluid actuated means, an electric motor for rotating said cage, and an electric controlled valve for controlling the supply of fluid, said motor and valve control having a common control means whereby the cage 125 cannot be raised during operation of the motor. 130

5. In an extractor, the combination of a curb, an apertured main cover therefor, a load-carrying cage rotatably mounted within said curb, said cage being adapted also for raising and lowering movement out of and into said curb, an arm adapted to extend through the aperture of the main cover for engagement with said cage for raising and lowering the same, and means adapted to extend between said arm and main cover so as to lock the main cover in closed position. 25
6. In an extractor, the combination of a curb, an apertured main cover therefor, a load-carrying cage rotatably mounted within said curb, said cage being adapted also for raising and lowering movement out of and into said curb, an arm adapted to extend through the aperture of the main cover for engagement with said cage for raising and lowering the same, and means slidably mounted upon said main cover and adapted to extend between said arm and main cover 30 so as to lock the main cover in closed position. 35
